ASSIGNORS TO V. & M. CO. INC., A CORPORATION OF NEW YORK.

NON-SKID-ELEMENT CONNECTOR.

1,291,293.

Specification of Letters Patent. Patented Jan. 14, 1919.

Application filed February 16, 1918. Serial No. 217,556.

To all whom it may concern:

Be it known that we, ROBERT I. VINCENT and WILLIAM L. McCOWAN, both citizens of the United States, and residents of Hudson Falls, in the county of Washington and State of New York, have invented a new and Improved Non-Skid-Element Connector, of which the following is a full, clear, and exact description.

10 This invention relates to non-skid devices for vehicle wheels and particularly to wheels of traction vehicles.

15 Among the objects of the invention is to provide improved facilities for quickly attaching non-skid devices to the peripheries of wheels or removing such devices therefrom, the means constituting a most reliable device for holding the non-skid devices.

20 Another object of the invention is to provide an attachment means for non-skid chains, or their equivalent, which when the non-skid devices are not employed will detract as little as possible from the appearance of the wheel structure.

25 With the foregoing and other objects in view the invention consists in the arrangement and combination of parts hereinafter described and claimed, and while the invention is not restricted to the exact details of 30 construction disclosed or suggested herein, still for the purpose of illustrating a practical embodiment thereof reference is had to the accompanying drawings, in which like reference characters designate the same 35 parts in the several views, and in which—

Figure 1 is a side elevation of a traction wheel having our improvement applied thereto, the direction of movement of the wheel being indicated by arrows.

40 Fig. 2 is a detail view of the device as it would be seen from the plane 2—2 of Fig. 1.

Fig. 3 is a side elevation of the device as it would be seen looking in the direction of the arrow 3 adjacent to Fig. 2.

45 Fig. 4 is a view of the device in the position indicated from the plane 4—4 of Fig. 1; and

Fig. 5 is a plan view or diagram of the blank from which the bracket or main portion of the attachment is made.

Referring now more particularly to the drawings we show an attachment means for a non-skid chain 10 of any suitable nature, said attachment means comprising two main 50 portions, namely a bracket 11 and a fas-

tener 12 to secure the same to a spoke 13 adjacent to the felly 14 of the wheel. The fastener while indicated as of a U-bolt structure including a strap 15 and two parallel legs 16, obviously may assume different 60 forms according to the nature or shape of the spoke to which it is to be secured.

The bracket 11 is formed preferably from a piece or strip of sheet metal and comprises three main parts each arranged at a right 65 angle to the plane of the next adjacent part. These three parts may be described as a plate 17, a shank 18, and a hanger 19, the plate and hanger being arranged in spaced 70 parallel planes as indicated.

The plate 17 is provided with holes 17' near its ends through which the legs 16 of the U-bolt pass, and against the inner face of the plate a pair of nuts 20 are screwed upon the threaded ends of the legs to 75 secure the bracket against one side of the spoke while the shank portion 18 thereof lies snugly against the felly 14.

The hanger member 19 includes a pair of hooks 21 the points of which are directed 80 toward each other as well as toward the center of the wheel or away from the tire or periphery of the wheel around or over which the non-skid element 10 is secured.

While the non-skid element 10 is illustrated in the form of a chain we wish it to be understood that it may assume various specific forms so long as it includes a pair of end links or loops 22 which are adapted to be hooked over the hooks 21.

In the practice of our invention the non-skid elements may be secured to the wheel either from the ground or from the running board of the vehicle with facility, the loops 22 thereof being attached over the hooks 21 95 in succession, one loop being first applied, the non-skid attachment being passed then around the tire or periphery of the wheel and the other loop attached to its hook. The construction of the attachment means 100 and the manner of attaching the same to the spoke provide for ample strength to resist any or all strain that may be applied to the non-skid element because of the traction between the wheel and the roadway.

Any suitable means may be provided to hold the loops 22 upon the hooks so as to prevent accidental disconnection thereof, but providing for the detachment by the operator whenever desired in a quick and easy 110

manner. To this end we provide a retainer 23 made preferably of a single piece of spring metal the middle portion of which is fastened to the shank 18 as by means of a rivet 24, or its equivalent. The ends 23' of the retainer are bent inward from the point of attachment at the rivet 24 so as to extend over the hanger 19 and along the points of the hooks as will be understood in comparing Figs. 2 and 4. Each end 23' therefore of the retainer constitutes a keeper or tongue closing the loop of the hook over which it coöperates. The structure of the retainer is such that it lies against the point of the hook and prevents any possible accidental disconnection of the non-skid device loop or link 22, but since it is flexible it is comparatively easy for the operator to spring each of the tongues toward the other tongue sufficiently far to remove the link or loop 22 from the hook thus guarded if desired.

We are aware that it is not broadly new to provide non-skid link elements with means for attaching the same to or detaching the same from fastening devices carried as permanent parts of the wheel structure,

but so far as we have been advised the present devices on the market are more or less unsightly and complicated, the latter fact being occasion for likelihood of failure to operate as they should. In our construction there is no possibility of the device failing to receive the non-skid element when it is desired to be applied thereto or to prevent the detachment thereof when required. Furthermore there is nothing to break, become disconnected, or otherwise get out of order.

We claim:

In an attachment device, the combination of a bracket comprising three integral features, namely a plate, a hanger spaced in a parallel plane from the plate, and a connecting shank, said hanger including a pair of hooks having their points directed toward each other, a spring keeper having its ends bearing against the points of the hooks, a fastener to secure the retainer to said shank, and a fastener to secure the bracket in position.

ROBERT I. VINCENT.
WILLIAM L. McCOWAN.
